F. W. BIELITZ.
 SAFETY DEVICE FOR USE IN CLEANING WINDOWS.
 APPLICATION FILED MAR. 14, 1919.
1,343,546. Patented June 15, 1920.

UNITED STATES PATENT OFFICE.

FREDERICK W. BIELITZ, OF JERSEY CITY, NEW JERSEY.

SAFETY DEVICE FOR USE IN CLEANING WINDOWS.

1,343,546.

Specification of Letters Patent. Patented June 15, 1920.

Application filed March 14, 1919. Serial No. 282,582.

To all whom it may concern:

Be it known that I, FREDERICK W. BIELITZ, a citizen of the United States, and resident of Jersey City, county of Hudson, State of New Jersey, have invented a certain new and useful Improvement in Safety Devices for Use in Cleaning Windows, of which the following is a specification.

My invention relates to safety devices and has for its object to provide a simple and efficient device intended primarily for use in cleaning windows and designed to serve as an outside seat for the cleaner when cleaning the outsides of said windows. According to the custom existing at present, the cleaner, for instance, a woman, seats herself upon the window sill with her body outside of the window and her limbs depending from the sill inside of the room, when it is desired to clean the windows on the outside. Because of the general formation of the window sill and the lack of control which the cleaner has in the indicated position, this practice is dangerous and oftentimes results in accidents; furthermore, the position of the cleaner is uncomfortable because of the formation of the sill, and is very tiresome and fatiguing because of the effort required to maintain a balance in addition to the efforts expended in the actual work of cleaning.

The principal object of my invention is to overcome these dangers and objections and to render the operation of cleaning windows on the outside safe and comfortable. My invention further contemplates a device which is readily adjustable to different dimensions so as to fit windows of different sizes and types. My invention will be fully described herein-after and the features of novelty will be pointed out in the appended claims.

In the accompanying drawings, which, for illustrative and descriptive purposes, show an example of my invention, Figure 1 is an inside elevation of my device showing it in operative combination with a window; Fig. 2 is a plan view thereof; Fig. 3 is a view showing the device folded up when not in use; Fig. 4 is a cross-section on the line 4—4 of Fig. 1; Fig. 5 is a detail bottom view; and Fig. 6 is a detail view illustrating the locking means whereby my device may be secured in an adjusted position.

As shown in the illustrated example, the device comprises a seat consisting of two sections 10 and 10^a formed of a series of bars 11 and 11^a which overlap each other, as shown

in Fig. 1. At the contiguous, overlapping portions, said bars 11 and 11^a are provided with slots 12 and with pins or rivets 13, the arrangement being such that the rivets 13 of the bars 11 pass through and are slidable in the slots 12 of the bars 11^a and the rivets 13 of the bars 11^a pass through and are slidable in the slots 12 of the bars 11. The device further includes a back consisting of two sections 14 and 14^a hinged at 15 and 15^a respectively to the seat sections 10 and 10^a; the back sections 14 and 14^a are also formed of parallel bars which overlap each other and are provided with slots 16 and pins or rivets 17, the construction here also being such that the rivets 17 of one section pass through and are slidable in the slots 16 of the other section.

With the illustrated and described arrangement, the seat sections and back sections are capable of being adjusted to vary the dimensions of the device and to adapt it for windows of different sizes and types. The frictional engagement of the parts alone may be relied upon to maintain the seat and back sections in their adjusted positions or, as is preferred, a mechanical locking device may be provided for this purpose. As shown in the illustrated example, this device comprises a rack 18 and a coöperating pawl 19 pivotally mounted upon a recessed member 20 into which the rack 18 telescopes; these elements are each connected with one of the seat and back sections in operative relation to each other, as shown in Fig. 1. For instance, as shown, the racks 18 are connected at 21 with the seat section 10 and back section 14, respectively, and the recessed members 20 are connected at 22 with the seat section 10^a and back section 14^a, respectively. Thus, as the sections 10—10^a and 14—14^a are drawn or moved outwardly relatively to each other, the pawls 19 will pass over the racks 18 and will finally lock the sections in their adjusted positions against relative inward movement; to permit a return movement of said sections, the pawls 19 are manually swung out of contact with said racks 18 in the well-known way. Suitable springs 23 or equivalent devices may be employed for maintaining said pawls in contact with said racks and for returning them into contact therewith.

The device further includes end members 24 hinged at 25 to the seat sections 10 and 10^a respectively and provided with ears 26 having apertures for the accommodation of

studs 27 carried by the back sections 14 and 14^a. Thus, when the parts are in their operative positions, the studs 27 project through the ears 26 and thereby maintain the end members 24 against pivotal movement on the hinges 25. For the purpose of locking the back against pivotal movement on the hinges 15 and 15^a, the back sections 14 and 14^a may be provided with hooks 28 pivoted 10 at 29 and arranged to be inserted in suitable openings in the ears 27; with this arrangement, the hooks 28 prevent the withdrawal of the studs 27 from the apertures in the ears 26 and thus lock the back sections against movement on the hinges 15 and 15^a.

The end members 24 are further provided with projecting lugs 30 arranged to engage and fit behind a suitable part A of a window casing when the device is in use as will be 20 more fully explained hereinafter. Supporting members 31 are located beneath the seat sections 10 and 10^a and are provided at one end with flanges or hooks 32; these members 31 are adjustable transversely to the seat sections by means of slots 33 and rivets 34 which serve also to secure said members to said seat sections.

In the preferred construction, braces 35 are hinged at 36 to said members 31 and are 30 formed with stepped edges 37, as shown in Fig. 4; these braces 35 may be locked in their operative positions, for instance, by means of projections 38 carried by the braces and arranged to enter notches 39 formed on the adjacent non-rotating members of the hinges 36. In order that the projections 38 may automatically find the notches 39 and thus do away with the necessity for careful manipulation of the parts, 40 coil springs 40 may be provided. These springs 40, by exerting pressure in the direction of the axes of the hinges 36, cause the projections 38 to snap into the notches 39 as soon as these elements register with each 45 other and also serve to maintain said projections in said notches against unintentional withdrawal therefrom.

Friction alone may be relied upon to 50 maintain the supporting members 31 in their adjusted positions although positive locking devices are preferred for this purpose. As shown in the illustrated examples, these locking devices comprise toothed racks 41 located on the members 31 and co-operating 55 pawls 42 pivoted at 43 upon the seat sections 10 and 10^a, as illustrated in Fig. 5; suitable springs 44 are provided for maintaining said pawls in contact with said racks and for returning them into engagement therewith.

60 In utilizing the device, the seat sections 10-10^a and back sections 14-14^a, are adjusted so as to bring the end members 24 into proximity with the opposite vertical portions A of the window casing, the lugs 30 fitting or extending behind these portions A

of the window casing as shown in Figs. 1 and 2 and resisting any outward movement of the device. By adjusting the supporting members 31 to bring the flanges 32 thereof either behind or upon a suitable portion of 70 the inner sill B of the window and so as to bring the stepped edges 37 of the braces into contact with the edge of the outer sill C as shown in Fig. 4 the device is braced against movement in a horizontal direction; the 75 angle of the seat sections 10-10^a in transverse directions may be adjusted by engaging different steps of said edges 37 with the edge of the sill C, as will be apparent from Fig. 4.

80 In its operative position, the device is supported upon the sills B and C and is held against outward movement by the lugs 30 and thus forms a comfortable and safe seat for the cleaner when cleaning windows on 85 the outside, the position of the cleaner being a natural sitting position in which the body is under complete control and in which no effort is required to maintain a balance as is ordinarily the case. The cleaner is thus enabled to devote his or her entire energies to the work of cleaning and consequently is enabled to do a greater amount of work than is ordinarily possible because a large percentage of energy is expended by the cleaner in 95 maintaining himself or herself against falling.

It will, of course, be obvious that the various elements of the device may be constructed otherwise than of spaced bars and 100 also that suitable cushions may be applied to the seat.

When not in use, the device may be compactly folded, as shown in Fig. 3 and stored away in a minimum of space until again 105 needed.

While my device is primarily intended for use in cleaning windows, it is obvious that it may be used in any other connections when safe and comfortable access to the outside of a window is desired.

110 Various changes in the specific form shown and described may be made within the scope of the claims without departing from the spirit of my invention.

115 I claim:

1. A device of the kind described comprising seat, back and end sections, stepped braces pivotally connected with said seat section for supporting said device from below, 120 the pivotal axes of said braces extending lengthwise thereof whereby said braces are movable to inoperative positions beneath said seat sections and means for connecting said device with a window.

125 2. A device of the kind described comprising seat, back and end sections, stepped braces pivotally connected with said seat sections for supporting said device from below, resilient locking devices for locking 130

said braces in their operative positions and means for connecting said device with a window.

3. A device of the kind described comprising seat, back and end sections, supporting members located beneath and carried by said seat sections and adjustable transversely thereto, stepped braces pivotally connected with said supporting members for

supporting said device from below and movable to inoperative positions beneath said seat sections, means for locking said braces in their operative positions and means for connecting said device with a window. 10

In testimony whereof I have hereunto set 15 my hand.

FREDERICK W. BIELITZ.
